Inventor:

Joseph Schwarz.

UNITED STATES PATENT OFFICE.

JOSEPH SCHWARZ, OF SIOUX FALLS, SOUTH DAKOTA.

SASH-HOLDER.

SPECIFICATION forming part of Letters Patent No. 554,317, dated February 11, 1896.

Application filed March 4, 1895. Serial No. 540,546. (No model.)

To all whom it may concern:

Be it known that I, JOSEPH SCHWARZ, a citizen of the United States, residing at Sioux Falls, in the county of Minnehaha and State 5 of South Dakota, have invented a new and useful Window-Screen and Storm-Sash Lock, of which the following is a specification.

My invention relates to a lock which is to be used principally in securing outside window-screens and storm-sash to window-frames or for similar purposes by means of concave spring-wedges applied under a fixed staple, and the objects of my invention are, first, to provide a lock which will at all times hold the 15 screen or sash against the blind-stop or other underlying surface; second, which lock without removing from frame will successively hold window-screens and storm-sash; third, which without further adjustment will hold 20 in the same opening screens and sash of varying thickness; fourth, which when not in actual use will not easily become detached, and, 25 fifth, a lock which can be placed in such position as will not interfere with the easy introduction or removal of sash or screens. I attain these objects by the mechanism illustrated in the accompanying drawings, in which—

Figure 1 shows a perspective of the lock; 30 Fig. 2, a side view; Fig. 3, a top view; Fig. 4, an end view showing point of wedge; Fig. 5, an end view showing heel of wedge; Fig. 6, a view showing the application of lock to sashes or screens of varying thickness; Fig. 35 7, a perspective of an alternate staple which may be used in place of the one shown in the other views.

Similar letters refer to similar parts throughout the several views.

40 The staple A is driven into the outside casting as far as may be necessary for the adjustment of wedge to the average thickness of sash. This staple may, if deemed desirable, be replaced by a square iron eye attached by 45 means of screws, as shown by Fig. 7. The head B of staple is slightly concave, thereby assisting in throwing the wedge C, hereinafter mentioned, against the posts A of staple.

The concave wedge C (by "wedge" C is principally meant all of that part of lock referred to by letters D, E, F, G, and H, these letters

only referring for better illustration to individual parts of the wedge C) is to be made of tempered material with corrugated or serrated edges, the heel D turned down and widened and made slightly concave at the base E, while the point F is turned up and slightly spread, with a depression or indentation at G, after which it is turned down and returned back to H to form a long bearing 55 for the point of wedge. The wedge is inserted into the staple by pressing the two edges of the point F together sufficiently to overcome the slight projections above and below the indentations G and driven in between the 60 posts A of staple until the point and heel of wedge press firmly against the stationary outside window-casing and sash or screen, respectively.

As the wedge C is made slightly wider than 70 the distance between the posts A of staple and sprung into place, the corrugated or serrated edges of wedge C are kept in close contact and engage successively in the posts A and lock the wedge C when it has been driven 75 in sufficiently far under the head B of staple or at any desired point. The contact of wedge C against the staple-posts A is further increased by concave form of the head B of staple. To withdraw the wedge, the heel at D 80 and, if necessary, the point at F are pressed together sufficiently to disengage the serrated or corrugated edge of wedge C from posts A, and the wedge C is then withdrawn. When the sash or screen is to be withdrawn from 85 the frame or casing I, the wedge C is placed in the position shown by dotted lines, Fig. 2, when the indentation G engages in the posts A of staples and holds the wedge C firmly in the upright position indicated by dotted lines, 90 Fig. 2, whereby it in no way interferes with the introduction or removal of sash or screen.

When it is desirable to remove the wedge C entirely from the staple, the wedge C is first placed in the position shown by dotted lines, 95 Fig. 2. Then the points F of wedge C are pressed together sufficiently to overcome the protrusion above the indentation G, after which the wedge C can easily be withdrawn from staple. Owing to the increase in width 100 of the point of the wedge above and below G, as also of the heel at D and E, the wedge C

cannot unawares become detached from the staple A. The constant pressure exerted by the wedge C against the post A of staple, owing to the slight excess of width of wedge C before introduction over distance between staple-posts A, will hold it in any desired position when not in use, and the form of the point and heel of wedge at F G H and D E, respectively, permit the heel and point to be pressed together without necessitating undue force.

The use of this lock, although primarily intended for the use of holding in position storm-sash and screens, is not necessarily restricted to that purpose, but may be used advantageously under similar circumstances, although for different purposes.

I am not aware that a wedge and staple of this form and construction has heretofore been used for the purpose of securing win-

dow-screens and storm-sash or similar purposes, and

What I claim as my invention, and desire to secure by Letters Patent, is—

The combination in storm-sash and window-screene fasteners of a double spring, made of tempered wire or other suitable material having parallel corrugated or serrated edges, shaped as a wedge by turning the ends in opposite directions to form bearings, and a staple to engage the same in such manner, as to hold it in place, whether in use or not, the whole forming a device for holding in position and locking storm-sash, window-screens, or any similar structure, all substantially as set forth.

JOSEPH SCHWARZ.
